UNITED STATES PATENT OFFICE.

JOHN EDWARD RUSSELL, OF SCRANTON, PENNSYLVANIA.

GAME.

Application filed January 25, 1924. Serial No. 688,531.

To all whom it may concern:

Be it known that I, JOHN E. RUSSELL, a citizen of Great Britain, residing at Scranton, in the county of Lackawanna and State 5 of Pennsylvania, have invented certain new and useful Improvements in Games; and I do declare the following to be a full, clear, and exact description of the invention, such as will enable others skilled in the art to 10 which it appertains to make and use the same.

My invention aims to provide a simple and inexpensive, yet a highly amusing game embodying a ball-receiver into which balls 15 of celluloid or other suitable material are tossed, provision being made whereby the balls will descend from the receiver and roll onto separate playing fields. It is intended that the fields shall have independent colors 20 and that the balls shall be correspondingly colored, so that when a ball of one color reaches a field of the same color, a score is made. Instead of using colors, letters, numbers or other means may be provided to 25 identify the balls with the fields.

Another object of the invention is to provide novel means for discharging the balls from the fields and conducting them to a common point.

With the foregoing in view, the invention resides in the novel subject matter hereinafter described and claimed, the description being supplemented by the accompanying drawings.

Figure 1 is a front elevation of the game constructed in accordance with my invention.

Figure 2 is a plan view.

Figure 3 is a central vertical sectional 40 view.

Figure 4 is a sectional view through the ball-receiver showing a slightly different form of construction.

Figure 5 is a vertical section on line 5-5 45 of Fig. 4.

Figure 6 is a detail horizontal section on line 6-6 of Fig. 4.

In the construction shown in Figs. 1, 2 and 3, the numeral 1 designates a flat, inclined board suitably supported upon an appropriate base 2, said board having a convex lower edge provided with a front wall 3. From this wall, a plurality of partition walls 4 converge upwardly along the 50 upper side of the board 1 and segregate the latter into a plurality of separate fields

which may be designated by different colors, by numbers, by letters as indicated in Fig. 2, or in any other desired manner, it being sufficient that the fields are separately designated and that the balls 5 used in playing the game (Fig. 2) be similarly designated, so that when any ball rolls upon its corresponding field, a score may be registered for the person using said ball. 65

Rising from the rear end of the board 1, are a number of vertical passage members 6 which discharge onto the separate playing fields. If desired, the front sides of these passage members may be designated in 70 the same manner as the fields and balls, and in Fig. 1, letters have been used upon these passage members, corresponding to the letters above mentioned for said fields and balls. 75

The upper ends of the passage members 6, support a ball-receiver 7 which is preferably four-sided and of substantially funnel-shape. The rear side wall of this receiver is faceted as indicated at 8, so that 80 when the balls are thrown against the facets, they will bounce in numerous directions before descending from the receiver through one of the passage members 6. The facets 8 do not extend entirely to the lower end of 85 the back wall of the receiver 7, and said lower end of this wall, as well as the lower ends of the other walls are preferably of slightly less incline than the major portions of said walls, as indicated at 9, providing 90 additional bouncing surfaces for the balls. Suitable braces 11 may be provided for the receiver 7, one of these braces being shown connected with the portion 9 of the back wall of said receiver, while the other is connected 95 with said back wall at a higher point, the lower ends of both braces being secured to the base 2.

I prefer to provide the front wall 3, with ball outlets 12 from the individual fields, and gates 13 are employed to normally close these outlets. In the present showing, the gates 13 are all carried by a resilient wire 14 which extends along the front wall 3 and is rotatably mounted in appropriate bearings 15, one end of said wire having an appropriate handle 16, by means of which it may be turned to simultaneously open or close all of the gates 13. A trough 17 has been shown in front of the wall 3 to receive 100 the balls from the openings 12, when the gates 13 are opened, and the bottom of this 105 110
